I. R. Oakford.
Steam Generator.
Nº 71903   Patented Dec. 10, 1867.

United States Patent Office.

ISAAC R. OAKFORD, OF PHILADELPHIA, PENNSYLVANIA.

Letters Patent No. 71,903, dated December 10, 1867.

IMPROVEMENT IN STEAM-GENERATORS.

The Schedule referred to in these Letters Patent and making part of the same.

TO ALL WHOM IT MAY CONCERN:

Be it known that I, ISAAC R. OAKFORD, of Philadelphia, in the county of Philadelphia, and State of Pennsylvania, have made a new and useful Improvement in Steam-Generators; and I do hereby declare that the following is a full, clear, and exact description of the construction and operation of the same, reference being had to the accompanying drawings, making a part of this specification, in which—

Figure 1, plate 1, is a perspective view of my steam-generator.

Figure 2, plate 2, is an end view of same.

Figure 3, plate 2, is a longitudinal section.

The object of my invention is to construct a steam-generator, which will be simple, cheap, safe in construction, and security of life in case of explosion, and to generate steam quickly and easily, with no waste of fuel, easy of access in case of cleaning, and repaired, when necessary, at small expense.

To enable others skilled in the art to make and use my invention, I will now proceed to describe its construction and operation.

I build two brick arches, a top and bottom one, the top arch, A, fig. 3, being placed at a distance, of the length of the grate-bars, above the bottom one A'. These two arches, with the side walls, form the furnace F, and flue F L leading to the chimney G. To make the flue F L longer, the extremity of the arches nearest the chimney are carried out tangentially to them. The chimney G has its base on a level with the base of furnace F. The front part of the chimney G, where the flue F L comes in contact, is left open, this side being supported by an arch, A'', sprung across the flue F L. At the rear of the chimney G is a door, D, leading into and on a level with the bottom of flue F L. On the corners of the arches A and A' are placed angle-braces b, b', b'', and b''', of iron, connected together by means of rods, for the purpose of strengthening the walls and prevent the heat from cracking them. The braces b and b''', placed under the arch A', are made heavier and stronger in order to support the bottom part of the flue F L nearest the chimney, one end of said braces resting on wall W L, the opposite ends resting on and supported by piers P and P'. This part of the flue can also be supported by iron post or brick piers, placed at intervals, in addition to the braces. The side walls and arches A and A', enclosing the furnace F, are to be lined with fire-brick, and also made thicker than at any other part in order to give greater strength to resist the action of the heat. I make any number of cylindrical boilers, and of any diameter, in which sufficient strength can be secured without the aid of bolts or braces, having the ends made round in order to give greater strength, and also present more heating-surface. The ends of the boilers are also made in the form of pipes S and W, of a diameter considerably less than the diameter of the boilers. These pipes are made of a sufficient length to suit and serve for the water and steam-connections to the boilers. These boilers are placed inside of the flue F L, being made in length the height of the flue, the lower end to rest on the arch A', or bottom of flue F L, with the water-pipe W projecting through the brick-work, the ends coming even with the under side, so that they will in no way interfere with the scaffold used in constructing the arch. The upper end of the boilers touches on arch A, or upper part of flue F L, the steam-pipe S projecting through and a short distance above the brick-work. A short space should be allowed between the top part of the boilers, in the rows nearest the fire, and the brick-work, to allow for expansion of the boilers. The upper part of the flue F L, near the chimney G, will be supported by the boilers, which at this point are placed vertical. The feed-pipe F P is attached to the pipe W on the lower end of each boiler. The steam-pipe S P is attached in the same manner to the pipe S on the upper end of each boiler; the part connecting the rows nearest the furnace is made smaller. These connections are made by means of elbows and threads fitting into one another, or by means of flanges and bolts, or any other means to accomplish the same purpose.

I make my boilers of cast iron or any other metal. When made of cast iron there are no joints exposed to the direct action of the heat. This will be the case, also, where any other metal is employed, except that the side seam and rivets will be exposed, but no flange or screw-joint connections, all being made on the outside, removed from the direct action of the heat. Hence I am enabled to obviate the great difficulty of leaking, caused by the expansion of the metal opening the joints; also requiring less pumping of cold water into the boilers to supply the waste caused by said leakage. The first row of boilers is placed at an angle of about forty-five degrees, and a short distance above the level of the fire, the angle increasing with the arch until the back part

of the flue F L is reached, where it will assume a vertical position. The water-line is kept about the height, as shown by dotted lines L W, in each boiler, the rows directly over the fire being kept constantly full, there being less water in boilers furthest removed from the fire. Placing the boilers vertical, or nearly so as possible, allows the steam to have free exit from the surface of the water after it is formed. The feed-water coming in at the bottom, the steam has a clear passage to the pipes, having no obstructions, in the way of bolts or braces, to impede its progress; consequently there is no cramping of steam to cause priming, but allowing a free generation of steam. By the arrangement of the boilers in the flue F L, I am also enabled to gain a large amount of heating-surface, the products of combustion completely enveloping each and every boiler, and a complete absorption by the water of the heat produced.

If at any time these boilers become choked up with mud, scale, or any impediment, they can be cleaned very readily and in short time, by disconnecting the steam and water-connections and inserting a rod, brush, or sealing-bar in the top of the boiler, and force any water which may collect out at the bottom of the boiler. The last one or two rows, having no water-connections, act as a receptacle or steam-drum, and also superheat the steam to the extent necessary to give it its maximum working temperature. In case of fracture of one or more of the boilers, these can be detached very readily from the others, without any serious loss of time, and the remaining sound ones used. This will necessarily diminish the power of the generator to some extent, but still will overcome a great drawback when time is very precious. The fractured ones can be taken out, by the removal of a few bricks, and sound ones substituted.

To prevent condensation of the steam, the steam-pipes can be covered with felt or a light iron covering or any other means to accomplish the same purpose.

I reserve the right of making the arches A and A' of iron, the lower one, A', lined inside with fire-brick, the upper one, A, being formed of angle-iron, made in the form of the arch, and placed at intervals, and covered over with fire-brick.

I make my steam-generator of any size or power, and of any width or depth desired. The space between each boiler and the flue F L can be cleaned by opening the man-hole or door D, and inserting a brush between each row of boilers. The boilers are blown out through pipe B P.

Having thus described my invention, its construction and operation, what I claim as new, and desire to secure by Letters Patent of the United States, is—

A steam-generator, composed of a series of cylindrical boilers, of round ends, provided with openings for steam and water, and arranged in a vertical and inclined position, in the manner and for the purpose above set forth and described.
